UNITED STATES PATENT OFFICE.

ELISHA F. BEAVERSTOCK, OF HOLYOKE, MASSACHUSETTS.

WEFT BINDING AND SEVERING DEVICE FOR LOOMS.

1,191,652.

Specification of Letters Patent. Patented July 18, 1916.

Application filed April 3, 1913. Serial No. 758,598.

To all whom it may concern:

Be it known that I, ELISHA F. BEAVERSTOCK, a citizen of the United States of America, and resident of Holyoke, in the county of Hampden and State of Massachusetts, have invented certain new and useful Improvements in Weft Binding and Severing Devices for Looms, of which the following is a full, clear, and exact description.

This invention relates to improvements in automatic looms in which bobbins, from supplying means, are periodically delivered into the shuttle, causing expulsion of the shuttle bobbin from which the thread employed as the weft in the weaving by the loom has become exhausted. In looms of this kind, as well known, there is employed a so-called "feeler" which has a co-operative relation near one of the shuttle boxes with the more or less nearly thread filled bobbin so that when the thread shall have become exhausted to the extent that but very little of the thread remains on the bobbin, it will be instrumental in causing the rocking of the shaft which actuates a means for the discharge of the fresh filled bobbin from the bobbin supply into the shuttle,—while the latter is in the shuttle box,—and an expulsion from the shuttle of the exhausted bobbin.

Under this invention the loom is equipped with a device located on the machine adjacent the lay and operable to both temporarily bind the shuttle-supplied weft at a point adjacent the mouth of the shuttle box and to sever the said weft,—when the shuttle is to be replenished with a fresh bobbin,—holding the end portion of the weft which extends outwardly from the selvage; and the loom is also equipped with a second device, mounted adjacent the lay and between the ends of the shuttle box, operable to temporarily bind the portion of the weft between the first binding and cutting device and the point where the weft emerges from the eye of the shuttle, near one end thereof almost simultaneously cutting the weft, near where it is held. By the above mentioned provision a portion of the weft extending outwardly from the selvage, more or less nearly to the mouth of the shuttle box, is held against liability of becoming in any way entangled with the further filling as it is made into the cloth, to result in serious injury to the fabric; and the severed portion

of the weft between the mouth of the shuttle box and an intermediate part thereof and of the shuttle therein severed from connection with the bobbin, not only will not be drawn when the bobbin is discharged from the shuttle box, to be possibly entangled with the freshly supplied weft, but it will be held and carried to a proper out of the way position to further insure against any liability of entanglement with the filling as the weaving proceeds following a replenishment of the shuttle.

For the movements of the first and second weft binding and cutting devices to their places for effecting their binding and cutting operations and their retirement from such places, advantage is taken as the primary actuator, of the movements of the rocker shaft which is usually provided on automatic looms for operating the bobbin feeder, and the movements of which rocker shaft are controlled by the "feeler" (not shown),—it, of course, being fully understood that the said feeler-controlled shaft and its connection with the bobbin feeder form no part of this invention, and are as heretofore extensively employed and well known in automatic looms.

The invention is described in conjunction with the accompanying drawings and certain advantages thereof additional to those above indicated will be explained, and the invention will be finally defined in the claims.

In the drawings: Figure 1 is a diagrammatic plan view to indicate the relative locations of the lay with its shuttle box and the weft severing and binding devices in which my improvements are embodied. Fig. 2 is a partial front elevation showing principally loom arrangements as at present known and relatively to which locations of the devices pertaining to this invention may be the more clearly understood. Figs. 3 and 4 are sectional elevations as seen transversely of the loom, showing in conjunction with already known and used appliances what is herein termed the first binder and cutter, the appliances being shown in their different positions. Fig. 5 is a side view of the "first binder and cutter" as seen at the side opposite from that represented in Figs. 3 and 4. Figs. 6 and 7 are front end views of the "first cutter and binder" with the blade or movable part thereof in its different positions. Fig. 8 is a plan view showing the

attachment comprising the "second binder and cutter" and the bracket for supporting same on the frame of the loom adjacent the shuttle box end of the lay, Figs. 9 and 10 being side elevations of said device, one showing it in its retired position and the other in its projected position relatively to the shuttle box and shuttle therein, and just in readiness to have the binder and cutter thereof closed. Fig. 11 is a sectional elevation showing a detail of construction to be hereinafter referred to. Figs. 12 and 13 are cross sectional views through the jaw portions of the "second binder and cutter" with the relatively movable parts thereof shown in opened and closed positions. Fig. 14 is a view designed to more clearly illustrate the yielding character of an element comprised in the jaw opening and closing means of the second binder and cutter. It is to be stated that the elevation views, Figs. 3 and 4 are as seen looking inwardly from about the line $x-x$, while the elevations, Figs. 9 and 10 are as would appear looking from said section line $x-x$ outwardly.

Similar characters of reference indicate corresponding parts in all of the views.

The feeler controlled rockshaft is indicated at A in Figs. 3 and 4. It carries a curved lever arm B which by its bifurcated end engages the projecting stud a on a lever-like member C which is pivoted at b for rocking movement in a vertical plane. The said member C has at an intermediate part thereof a horizontal inwardly projecting stud-like member c carrying as a rigid right angular extension thereof a slotted part C².

D represents the bobbin feeder co-operative with the rotary pocket provided bobbin holder or magazine E intermittently rotative to successively bring down fresh bobbins to proximity to the shuttle box F on the lay Q. An articulation is made between the oscillatory appliances C, C² and the pivoted angular shuttle feeding element D through the element H, which by pivot d is hung to and carried by the depending arm of the angular lever-like member D, and by stud e has an engagement in the slot or aperture in the offset extension C² which is movable as one with the lever-like member C.

G represents a curved or angular arm which is made as one with the lever-like member C and extends upwardly and rearwardly toward the path of the shuttle across the lay. The extremity of this arm G has, rigidly connected therewith, but in slight separation therefrom, a block or plate G²; and the extremities of the arm proper and the supplement plate G² are formed bifurcated or recessed, as indicated at f, to form both binder and cutter jaws.

H represents a lever-like member connected by pivot g on the arm G and having by

the stud and slot construction indicated at h the swinging movement thereof limited, and the said member H has a projection i adapted to be contacted against by the lay when under the operation of the feeler-controlled rockshaft the arm G shall have been swung to within the range of the final or beating up portion of the movement of the lay. The member H is of bifurcated form as indicated in the upper portion of Fig. 5, whereby the blades j and j² are produced, these blades straddling the block or plate-like portion G² the blade j² being for cutting, and coacting, shear-like, with a knife or blade j³ on the jaw end of the arm G, while the blade j serves in conjunction with the blunt corner k of the block or plate G² as a binder so that when the two blades are simultaneously moved to their closed position there will first be a binding of the weft by the parts j and G², and a cutting of the weft near the point of the binding by and between the blade j² and the portion of the jaw G which may advantageously be provided with a hardened shear section j³. The corner k of jaw portion of the plate G² is understood as blunt, as seen in Figs. 6 and 7, and it is perceived that the binding edge k is higher than the edge of the shear portion j³ of jaw G, whereby the weft will be bound by blades j at the point k before it is cut by the blade j².

In Fig. 3, the above described parts (most of which are as already known and in use on a loom) are represented in their normal position, that is when the loom is running with a full bobbin, the binder and cutter jaws, however, being understood as closed, and in weft binding condition.

When the bobbin becomes exhausted of thread, through the controlling action of the feeler, a rocking of the shaft A is effected and the curved arm B is swung from the position, Fig. 3, to that indicated in Fig. 4, causing through the articulated parts C, C² and H² the swinging movement of the bobbin feeder D for the down feeding of the new bobbin into the shuttle and the expulsion of the exhausted bobbin therefrom. At this time the arm G is carried inwardly so that the bifurcated jaw ends thereof embrace or straddle the weft extending from the shuttle of the practically exhausted bobbin to the selvage, and almost at the same time by the engagement of the stud i with the lay the double jaws j² and j are closed, shear-like, the one to bind, and the other to cut the weft at a point adjacent the mouth of the shuttle box and between the latter and the selvage. Then, almost immediately, and on the bringing of the fresh bobbin into the shuttle, the feeler controlled rockshaft is effective to restore the connections and the arm G above described to their normal position, —Fig. 3, —the jaws remaining closed.

until the last fed bobbin also becomes exhausted, when on the next action by which arm G is swung inwardly, the projection i coacting with a cam plate n causes the opening of the jaws j, j² to open relation.

- 5 J² represents a bracket mounted on a suitable supporting part of the loom frame and comprising a part J made with a slideway J³ in which the slide bar K is movable for a reciprocating motion in a straight horizontal line at right angles to the line of projection of the shuttle, and one which is coincident with the part of the shuttle box in which an intermediate portion of the shuttle lies.
- 10 15 Embracing the forward extremity of the slide bar is an oscillatory device pivoted at n and comprising opposite side blades o, o², the extremities of which are suitably formed for coaction in the manner of shears with the forward end portion of the slide bar, which bar is of the cross sectional form shown in Figs. 12 and 13, such extremity having a blunt corner o³ and a sharp corner o⁴,—the sharp portion o⁵ of the one side plate o acting as a cutter shear in conjunction with the suitably sharp corner o⁴ of the slide bar, while the co-action between the extremity of the opposite side plate and blunt corner o³ is such that the weft, when 20 25 30 the parts are closed, shear-like, instead of being cut off, will be bound as would be done by a pair of shears so dull as to be ineffective for any cutting action. By reference to Figs. 12 and 13 it will be perceived that the blade o² reaches corner o³ of jaw K before cutting edge o⁵ reaches corner o⁴ of jaw, whereby the binding of the weft is effective before its cutting.

- 35 The two blades o and o², the extremities of which form movable jaws at opposite sides of the slide bar, are united to a spacing block o⁶, the upper edge o⁷ of which forms an abutment or stop for co-operation with the under side of the slide bar and to limit the movement in the closing direction of the bar of the jaw-comprising plates o, o², while a stud t forms an abutment for preventing the too wide opening movement of the jaw comprising plates,—see Fig. 11.
- 40 45 50 On the bracket J² below the forward jaw-carrying portion of the slide bar, connected by pivot p, is a more or less nearly upright lever N having at an intermediate portion thereof a laterally projecting stud P² which may be adjustably positioned and confined by reason of the slot p³ in the lever N.

- 55 60 65 There is another lever P pivoted at p⁴ on a lower part of the bracket J², such lever being more or less nearly parallel with the one N, and a link p² is pivotally connected with an intermediate part of the lever P and with the upper extremity of the lever N; and connection is made between the upper extremity of lever P and the slide bar K by the stud J⁴ of the slide bar which pro-

jects through the longitudinal slot J⁵ in one side wall of the slideway and engages in the slot J⁶ in the upper extremity of the lever P.

70 On the inner or forward end of the spacing block o⁶ below the slide bar K is an adjustable forwardly projecting abutment o⁹ to acquire an engagement with, or to be engaged by the lay when under the action of the feeler-controlled shaft the slide bar and its blade-like appurtenances are projected to the range of movement of the lay while coming to its final or beating up position.

75 The parts being understood, when the loom is regularly running, as in the normal position shown in Figs. 8 and 9, when the before described connected parts A, B, C, C², H and D are automatically operated at a time a new bobbin is to be fed into the shuttle whereby the element H is swung 80 from the position shown in Fig. 3 to that shown in Fig. 4, the said element H will strike the projection p² on the lever N, swinging the same to position shown in Fig. 10, therebf, through connections with the slide, projecting the same to the position shown in Fig. 10. This brings the abutment o⁹ to position to engage the lay whereupon the blades o, o² which had been 85 opened on the change of position Fig. 9 to 90 that of Fig. 10, will be closed for the severing by the blade o of the weft quickly after the binding of the weft adjacent the cutting off point by the blade o².

95 100 105 Adjacent and above the path of the blade carrying slide bar is a plate R having a cam lip R² which is downwardly and forwardly inclined and has a location adjacent the path of movement of the stud t, as seen in Fig. 8, and which projects at one side of the oscillatory member comprising the double blades. When said oscillatory device is in its normal position with the blades closed and is projected forwardly to the position represented in Fig. 10, the stud t 110 has an engagement under the cam lip R² and the jaws will be opened; but by the engagement of the abutment o⁹ with the lay the jaw blades are swung to closed position, Fig. 9, the stud t is so elevated that 115 on the return or retiring movement of the slide bar and the blade comprising device (which, when permitted, is accomplished by the retracting spring P⁴), the stud t will ride over the cam lip R² but without being 120 opened thereby, the part R with its cam lip being depressed.

125 The shank portion of the plate R is pivoted at u on the bracket, and it has a spring for holding it up to normal position,—this construction rendering it yieldable so that on the return movement of the parts the jaws still remaining closed, the stud t for its passage by the lip will depress the latter, the power required to open the jaws being 130

greater than that required to overcome the comparatively light spring u .

As represented in Fig. 11, the slide bar K carrying the oscillatory device comprising the blades o and o^2 at opposite sides of such slide bar, is made with a longitudinal slot v in which a spiral spring v^2 is provided in compression, one end of such spring bearing against the end of the slot and the other end bearing against a pin v^3 which is passed transversely through the slide bar at the opposite end of its slot and projects into and is movable in an arc shaped slot v^4 in the oscillatory blade comprising device,—this provision being effective for maintaining the blades o , o^2 in the positions to which they may be thrown, either opened or closed, and until such positions shall be reversed as desired for the proper operation of the mechanism.

It is understood that the spring exerts a pressure against the pin v^3 to keep it in either of the extremities of the slot, any displacement of the spring from its retaining position necessarily requiring that it be moved past the central or dead center portion of the slot boundary.

At the time when the feeler controlled rockshaft is swung to carry the articulated members between such shaft and the bobbin feeder to the position shown in Fig. 4, the element H, in such position being represented in Fig. 10, the open jaw slidable device K, o , o^2 is projected so that such jaws pass into and through an aperture w in the side of the shuttle box between the ends of the latter and more or less into an aperture w^3 in the side of the shuttle, as represented in Fig. 10.

The weft of the expiring bobbin is understood as lying, as usual, along the outer grooved face of the shuttle so that upon the engagement between the abutment o^2 and the lay, causing the movable jaws o and o^2 to assume their closed positions, the weft will be cut by the blade o , coacting with the sharp cornered portion o^4 of the slide bar K, after being bound by the blade o^2 which coacts with the blunt cornered portion o^5 of the slide bar K, as represented in Fig. 13.

So soon as the feeler controlled shaft A is swung to its normal position, whereby the element H is moved out of engagement with the stud p^2 which projects from the lever N, the slide bar and its closed jaws are retired in a line at right angles to and away from the shuttle carrying the bound end of the weft therewith and out of the line in which the weft is carried in the weaving action,— the jaws during such withdrawal remaining closed so that the short piece of the weft held by the binder will be carried forwardly to a point at which it will be without liability of becoming entangled with the weft of the new supply to be further woven into

the fabric being made in the loom. It will be dropped on the commencement of the next inward projection of the slide bar, when stud t impinges cam lip R^2 which is incapable of upwardly yielding.

The first cutter and binder severs the weft as near the selvage as practicable and binds, temporarily, the end adjacent the cut but which is toward the shuttle; while such end is held by the binder appurtenant to the first cutter, a portion of the weft farther outwardly located is severed by the second cutter after the end adjacent the second cut and still farther outwardly in the direction toward the outer end of the shuttle box is bound and retained during the time the next bobbin is supplying the loom and to be released and permitted to drop, free and clear away from the line of shoot of the weft being woven into the cloth.

I desire to be understood that the first cutter, carried on the swinging arm G, comprising the shear plate j^3 on the jaw end of said arm G and the shear blade j^2 coacting therewith, and the feeler shaft operated connections for positioning the arm G and the means for causing the closing of the cutter blade j^2 and for causing the opening thereof on the next succeeding inward movement of the arm, are as already well known, and extensively used in automatic looms,—but I have made the extremity of the arm G a support for the part G^2 and the blade j which constitutes the binder, and have so combined or united the newly provided binder blade j with the cutter blade j^2 that by moving in unison with the latter no new or added means is required for the opening and closing of the movable element of the binder.

The parts G^2 , j forming the "first" binder provide that the weft cut between the mouth of the shuttle box and the selvage will be suitably held to be in proper taut condition, and in proper line to be subject to the action thereon of the novel, herein termed "second," binder, and cutter which has its location opposite an intermediate part of the shuttle box and the shuttle therein.

I claim:

1. In a loom, in combination, the lay having thereon the shuttle box formed with a side opening at an intermediate portion thereof, a support on the loom frame having a slideway in a line at right angles to the length of the shuttle box opposite the apertured intermediate portion of such box, a slide bar movable in said slideway, its forward extremity forming a fixed jaw, an oscillatory device pivotally mounted on the slide-bar and comprising a jaw movably coacting with said fixed jaw, comprising a projection to constitute an abutment at a point offset from its pivot and distant from its jaw portion, and also having a laterally

projecting stud, a lever having an engagement with and for the reciprocation of the slide bar, and means for swinging the said lever,—the arrangement of the oscillatory device, when inwardly projected relatively to the lay, being such that the projection constituting its abutment and the lay will be brought to engagement for a closing of the movable jaw, a member mounted on the 10 slide bar support having an inclined lip, to be engaged by the lateral stud on said oscillatory device, for causing a reversed swinging of said device for an opening of its jaw during the movement of projection of the 15 slide bar.

2. In a loom, in combination, the lay having thereon the shuttle box formed with a side opening at an intermediate portion thereof, a support on the loom frame having 20 a slideway in a line at right angles to the length of the shuttle box opposite the apertured intermediate portion of such box, a slide bar movable in said slideway, its forward extremity forming a fixed jaw, an oscillatory device pivotally mounted on the 25 slide-bar and comprising a jaw movably co-acting with said fixed jaw, comprising a projection to constitute an abutment at a point offset from its pivot and distant from 30 its jaw portion, and also having a laterally projecting stud, a lever having an engagement with and for the reciprocation of the slide bar, and means for swinging the said lever,—the arrangement of the oscillatory 35 device, when inwardly projected relatively to the lay, being such that the projection constituting its abutment and the lay will be brought to engagement for a closing of the movable jaw, a member mounted on the 40 slide bar support and yieldable in a downward direction, having an inclined lip, to be engaged by the lateral stud on said oscillatory device, for causing a reversed swing-

ing of said device for an opening of its jaw during the movement to its inward position 45 of the slide bar.

3. In a loom, in combination, the lay having thereon the shuttle box formed with a side opening at an intermediate portion thereof, a support on the loom frame having 50 a slideway in a line at right angles to the length of the shuttle box opposite the apertured intermediate portion of such box, a slide bar movable in said slideway, its forward extremity forming a fixed jaw, an oscillatory device pivotally mounted on the 55 slide-bar and comprising a jaw movably co-acting with said fixed jaw, comprising a projection constituting an abutment at a point offset from its pivot and distant from 60 its jaw portion, a lever having an engagement with the slide bar, another lever linked to the first named lever and provided with a laterally projecting stud and a retracting 65 spring operatively applied to said link connected lever, the feeler controlled rock-shaft and an element movably actuated thereby adapted to engage with, and disengage from, the stud of the second-named lever for 70 effecting the inward projection of the slide bar and its oscillatory device,—the arrangement of the latter upon its inward projection, relatively to the lay, being such that its abutment constituting projection and the 75 lay will have an engagement for a closing of the movable jaw,—and means for causing a reversed swinging of the oscillatory device for an opening of the movable jaw during the movement of the slide bar.

Signed by me at Springfield, Mass., in 80 presence of two subscribing witnesses.
